Des. 1492

Henry G. Thompson, of New York, N. Y.
Assignor to
Hartford Carpet Company.
No. 1492 Letters Patent No. 127, dated Mar. 19, 1861.

The subject referred to in these Letters Patent and making part of the same.

To all whom it may concern:

Be it known that I, Henry G. Thompson, of the City County and State of New York, have invented or produced a new and original Design for a Pattern to be wrought into Ply Ingrain and other carpeting, in colors similar to those painted on the drawings accompanying this specification, or in other colors substituted in the place of those painted on the drawings herewith; and
